CLAIM

The ornamental design for a container for sanitizing spray, as shown and described.

DESCRIPTION

FIG. 1 is a top perspective view of a container for sanitizing spray showing my new design;

FIG. 2 is a bottom perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof; and,

FIG. 8 is a left elevated view thereof.

The broken lines illustrate portions of the container for sanitizing spray and form no part of the claimed design.

1 Claim, 8 Drawing Sheets
